VEHICLE DOOR POCKET

Otto F. Graebner, Detroit, Mich., assignor to The Murray Corporation of America, a corporation of Delaware

Application December 19, 1932, Serial No. 647,906

9 Claims. (Cl. 296—44)

This invention relates to vehicle bodies and particularly to a pocket for a door thereof which is rigid in construction, waterproof, which adds strength to the door and which is neat in appearance.

It has been the practice heretofore to provide a cardboard pocket or one of cloth in the cardboard facing of the inner panel of the door or to support a cloth on the face of the cardboard having elastic at the top thereof to draw the top edge of the pocket against the face of the finishing member. A pocket of this type was bulky while the cardboard or cloth pocket which projected through an aperture in the inner door panel was objectionable in view of the fact that the rain or the water employed in washing the car would run down between the door panels and cause the pocket to become wet.

The present invention employs an aperture in the inner panel and utilizes an inwardly pressed metal member which extends along the upper edge of the aperture and a considerable distance below its lower edge to form the pocket and also a strengthening member for the panel. Where heretofore the opening in the panel weakened the inner panel construction, the present construction adds strength to the panel and prevents it from readily kinking and bending. The extension of the inwardly pressed member below the lower edge of the opening forms a pocket which retains any element, even tools, without being apparent from the outer surface of the door.

Figure 1 is a broken plan view of an inner face of a vehicle door having a pocket which embodies features of my invention.

Fig. 2 is an enlarged sectional view of the structure illustrated in Fig. 1, taken on the line 2—2 thereof.

Fig. 3 is an enlarged broken view of the pocket illustrated in Fig. 1.

Fig. 4 is a sectional view of the structure illustrated in Fig. 3, taken on the line 4—4 thereof.

Fig. 5 is a sectional view of the structure illustrated in Fig. 3, taken on the line 5—5 thereof, and

Fig. 6 is a sectional view of the metal portion of the panel and door pocket which goes to make up my invention.

In Fig. 1, I have illustrated a door 10 having an inner panel 11 of conventional design. The panel 11 is provided with an aperture 12 which forms an entrance into the door pocket. A metal stamping 13 is drawn inwardly in pan shape, as illustrated in Figs. 2, 3 and 6 having an outer flange 14 thereabout which is mated at the top

and the sides with the material about the aperture 12. The pan extends substantially the distance of the opening therebelow to form a closure with the metal below the lower edge of the opening. The flange 14 is welded to the panel to form a water-tight connection therewith and to brace and strengthen the paneling. A cover of cloth or other material 15 is secured to the inner surface of the metal stamping 13 and to the inner face of the panel 11 which is encompassed thereby to form a finish for the pocket on its inner surface.

The outer covering on the door is retained by suitable securing elements about the opening in the panel and a door of rigid material is hinged thereto which completely covers the opening and forms a smooth appearance on the inner surface of the door. Suitable fastening means is provided for securing the edge of the door opposite to the hinge portion for retaining it in closed position. In this type of construction any water entering the door between the panels will have no contact with the inner surface of the pocket which thereby will always be retained dry and offers complete protection for objects stored therein.

Accordingly, the main objects of my invention are to provide a pocket for a door which is completely moisture proof and made of metal; to provide a pocket for a door which entirely encompasses the opening in the inner panel and to enclose the opening and to strengthen the panel; to provide securing elements about the aperture in the panel for receiving and retaining in firm position about the opening a cover element for the inner surface of the panel; to provide a hinged cover for said opening in said cover element which is substantially rigid and which forms a continuation of the paneling at the opening to form a smooth outer surface to the cover element; and, in general, to provide a waterproof pocket for a door which is neat in appearance, which is flush with the inner surface of the door and which adds strength to the door paneling.

Other objects and features of novelty of my invention will be either specifically pointed out or will become apparent when referring, for a better understanding of my invention, to the following description in conjunction with the accompanying drawing, wherein:

Apertures 16 are provided in the panel at the sides and above the opening beyond the junction with the flange 14. Suitable outwardly and upwardly extending fingers 17 are provided in the panel 11 below the lower opening for the purpose of securing a finish panel to the inner panel of

the vehicle door. The finish panel may be made of a sheet of material 18 such as cardboard, heavy paper or the like, which entirely covers the panel 11 except for the opening 12. A covering material 19, which is preferably of cloth, felt or the like, although any other material may be employed, is placed on the material 18 except for the opening 21 which mates with the opening 12 in the panel 11. A frame 22 of cardboard, or like material, is stitched to the material 18 about the opening 21 to retain the material 19 thereagainst and to strengthen the material about the opening. A cover 23, having a substantially rigid central portion 24 which may be heavy cardboard, fibre or the like, is covered with the material 19 and stitched along its lower edge to the frame 22 and material 18 to form a hinge. The frame 22 is spaced from the material 18 at the lower edge by the cloth material 19 which is provided therebetween to permit the lower edge of the frame 22 to be received by the upstanding fingers 17 to secure the material 18 against the panel 11 along the lower edge of the pocket. Suitable expanding clips 25 are provided in the material 18 to mate with the aperture 16 provided in the panel 11 to extend therethrough to secure the finish paneling to the panel 11. In this manner the finish paneling is first moved downwardly to have the frame 22 secured by the finger 17 and thereafter the securing clips 25 are pushed through the apertures 16 to thereby secure the paneling tightly against the panel 11 about the pocket. Other clips 25 are employed about the outer edge of the finish paneling to extend through aperture 16 at the edge of the paneling 11 to secure the finish paneling to the marginal edges of the door.

The closure element 24 of the finish paneling is provided with a glove fastener 27, or a similar fastener, to be mated with a portion thereof secured to the paneling 11 to thereby retain the cover in closed position. A suitable tab 28 may be employed in the vicinity of the fastener 27 to effect its release when the tab 28 is pulled upon by an operator. The cover element 24 is then swung downwardly from the opening in the finish paneling and the opening 12 of the metal panel 11 of the door so that the pocket will be accessible to an operator.

Referring to Fig. 6, it will be noted that the pressed stamping 13 is so formed as to have the flange 14 disposed in a plane. When the inner panel of the door slopes to conform to the curvature of the body, the panel 11 is offset outwardly, as at 29, to have the metal thereof disposed in the plane of the flange 14 so as to be engaged thereby. The members 13 can therefore be constructed from a single die and be employed on inner door panels of any curvature in view of provision of the ledge 29 on the panel which will be engaged by the flange 14 of the member 13.

The pocket thus formed is flush with the inner surface of the panel and presents a very neat appearance thereto since the cover element 24 for enclosing the pocket is flush with the inner cover element of the door. The pocket is, however, readily accessible through the release of the button fastener 27 through the pulling of the flap 28 and the material within the pocket is protected by the metal element 13 both from damage and from moisture. The metal element 13 materially braces the panel and adds to the strength of the door. The finish cover panel is releasably secured to the door through expanding elements which retain the cover in unit engagement with the panel at the edges of the door and

about the opening of the pocket. The pocket is disposed toward the lower end of the door to permit the movement of the window downwardly within the door without interfering with the pocket.

While I have described and illustrated but a single embodiment of my invention, it will be apparent to those skilled in the art that various changes, omissions, additions and substitutions may be made therein without departing from the spirit and scope of my invention, as set forth in the accompanying claims.

I claim as my invention:

1. The combination with an inner and outer metal panel of a vehicle door, the former having an aperture therein, of a dish-shaped metal element disposed between said panels of greater vertical dimension than the vertical dimension of the opening secured to said inner panel and encompassing said opening.

2. The combination with an inner and outer metal panel of a door having a window therein, the former having an aperture below the lowermost position of the lower window edge thereof, of a dish-shaped metal element disposed between said panels of greater vertical dimension than the vertical dimension of the opening secured to said inner panel and encompassing said opening.

3. The combination with an inner and outer metal panel of a door having a window therein, the former having an aperture below the lowermost position of the lower window edge thereof, of an inwardly drawn metal element disposed between said panels having a lateral flange secured to said inner panel and covering said opening to form a receptacle and a bracing element for the panel.

4. The combination with an inner and outer metal panel of a door having a window therein, the former having an aperture below the lowermost position of the lower window edge thereof, of a dish-shaped metal element disposed between said panels having a greater vertical dimension than the vertical dimension of the opening and secured to said inner panel and encompassing said opening, and a finishing element for the inner panel releasably secured thereto about the aperture of the panel and having an aperture therein.

5. The combination with an inner and outer metal panel of a door having a window therein, the former having an aperture below the lowermost position of the lower window edge thereof, of a dish-shaped metal element disposed between said panels having a greater vertical dimension than the vertical dimension of the opening and secured to said inner panel and encompassing said opening, a finishing element for the inner panel releasably secured thereto about the aperture of the inner panel and having an aperture therein, and a hinge element secured to said finish element for covering said aperture.

6. The combination with an inner and outer metal panel of a door having a window therein, the former having an aperture below the lowermost position of the lower window edge thereof, of a dish-shaped metal element disposed between said panels having a greater vertical dimension than the vertical dimension of the opening and secured to said inner panel and encompassing said opening, a finishing element for the inner panel releasably secured thereto about the aperture of the inner panel and having an aperture therein, a hinge element secured to said finish element for covering said aperture, and se- 75

curing means for said element for retaining it in closed position.

7. The combination with an inner and outer metal panel of a door having a window therein, the former having an aperture below the lower-most position of the lower window edge thereof, of an inwardly drawn metal element disposed between said panels having a lateral flange secured to said inner panel and covering said opening to form a receptacle and bracing element for the inner panel, and a finish element for the inner panel having releasable engaging means for attachment to said panel about said aperture.

8. The combination with an inner and outer metal panel of a door having a window therein, the former having an aperture below the lower-most position of the lower window edge thereof, of an inwardly drawn metal element disposed between said panels having a lateral flange secured to said inner panel and covering said opening to form a receptacle and bracing element for the inner panel, a finish element for the inner panel having releasable engaging means for attachment to said panel about said aperture, a hinge element secured to said finish element and covering said aperture, and securing means on said hinge element for releasably retaining it in closed position over said aperture.

inner panel, a finish element for the inner panel having releasable engaging means for attachment to said panel about said aperture, and a hinge element secured to said finish element for covering said aperture.

9. The combination with an inner and outer metal panel of a door having a window therein, the former having an aperture below the lower-most position of the lower window edge thereof, of an inwardly drawn metal element disposed between said panels having a lateral flange secured to said inner panel and covering said opening to form a receptacle and bracing element for the inner panel, a finish element for the inner panel having releasable engaging means for attachment to said panel about said aperture, a hinge element secured to said finish element and covering said aperture, and securing means on said hinge element for releasably retaining it in closed position over said aperture.

OTTO F. GRAEBNER.

CERTIFICATE OF CORRECTION.

Patent No. 2,019,674

November 5, 1935.

OTTO F. GRAEBNER.

It is hereby certified that error appears in the printed specification of the above numbered patent requiring correction as follows: Page 1, first column, line 33, beginning with the word "Figure" strike out all to and including "surface." in line 11, second column, and insert the same after line 49, of said second column; and that the said Letters Patent should be read with this correction therein that the same may conform to the record of the case in the Patent Office.

Signed and sealed this 10th day of December, A. D. 1935.

Leslie Frazer

Acting Commissioner of Patents.
